SHOWCASE CONSTRUCTION

Anthony Vanderveld, Grand Rapids, Mich., assignor to Grand Rapids Store Equipment Company, Grand Rapids, Mich., a corporation of Michigan

Application January 18, 1939, Serial No. 251,538

9 Claims. (Cl. 312—140)

This invention relates to improvements in showcase constructions, and is more particularly concerned with a novel means for tying together the opposed front upper corners of the ends of a showcase which has a glass top, and front, and ends and may be provided with overlapping sliding doors in the back. The ends are vertical and may be either substantially wholly of wood, or have wood frames surrounding glass. It is at the upper front corners of the ends my invention is to be applied for not only supporting and holding said upper corner portions against outward spreading, but for drawing the end members of the showcase against the ends of the top glass plate, and for securing and holding them in such position. And if at any later time it is necessary to further adjust the connecting and securing means which I have invented, it may be very readily accomplished.

10 The invention and the preferred structure embodying the same may be understood from the following description, taken in connection with the accompanying drawings, in which:

Fig. 1 is a perspective view of a showcase from the front and looking downwardly thereon to which my invention has been applied.

Fig. 2 is a fragmentary plan of the showcase, the top glass being removed but illustrated in dotted lines.

30 Fig. 3 is a vertical longitudinal section immediately back of the front glass plate of the case.

Fig. 4 is a transverse vertical section from front to rear and adjacent the front end, substantially on the plane of line 4—4 of Fig. 2.

Fig. 5 is a transverse section from front to rear of the showcase and adjacent one end thereof.

Fig. 6 is a vertical section substantially on the plane of line 6—6 of Fig. 5, looking in the direction indicated by the arrows.

Fig. 7 is a plan view showing my invention applied to a different form of showcase than that shown in Fig. 1, and

Fig. 8 is a perspective view of the tightening and reinforcing means used therewith.

Like reference characters refer to like parts in the different figures of the drawings.

The ordinary showcase as shown in Fig. 1 has a base 1, vertical ends 2, and a glass top 3 which extends between the ends and, as shown, is received in rabbeted recesses made longitudinally of the ends 2, there being left upwardly extending lips 4, one at the outer side and upper edge of each of the ends 2 and the full length thereof. The front is of glass, while at the back the usual over-

lapping sliding doors are slidably mounted, the construction and installation of which form no part of the present invention.

A horizontal bar 5 extends between the rear upper corner portions of the ends 2 and over it and at its rear portion has a finishing bar 6 secured thereto, the rear edge thereof coming against the front edge of the bar 6. This provides a secure connection between the ends 2 at their rear upper corners.

In one end, the right hand end 2, as shown in Fig. 1, a longitudinal groove is made at the upper edge thereof extending substantially the full length but terminating slightly short of the front of the end 2, in which groove a rod 7 is mounted, extending at its back end through the bar 5, and having a transverse slot 8 therein for the reception of the end of a screw driver. The front end of rod 7 is slotted and one end of a length 9 of a flat ribbon of metal is connected thereto, being partially rolled therearound, as at 10, and having the immediate end portion received in the slot (see Fig. 3). The ribbon member 9 extends underneath the glass top 3 substantially the full length thereof, to and over the upper end of the opposite end 2 of the showcase, and is anchored by bending around an anchor block 11 which is inset in the upper edge of said opposite end 2 and secured in place by screws 12. The rod 7 may be turned by engaging the slot 8 with a screw driver to tension the metal ribbon 9 and draw the front upper corner portions of the ends 2 toward each other and bring the upstanding ribs 4 snugly against the end edges of the glass top 3.

At the rear end of the rod 7 a block 13 is inset in the end 2 of the showcase which carries said rod, and also in the adjacent end of the cross bar 5, (Figs. 5 and 6) and is secured in place by a screw 14. The front upper portion of the block is cut away and in the recess thus made a locking member 15 is placed having its upper end concaved to conform to the curvature of the rod 7, its lower end being cut downwardly and forwardly at an angle to the horizontal and vertical, and fitting against a correspondingly shaped inclined end in the recess, as indicated at 16 in Fig. 5. An adjusting screw 17 passes from the rear through the block 13 and threads into the locking member 15. By tightening such screw the locking member 15 is moved upwardly to bear against the rod 7 and hold it against rotation. Loosening the screw 17 releases the hold which is made against rotation of the rod 7. Thus the rod 7 may be turned to tighten the ribbon tension member 9 and held in any position to which adjusted by 55

tightening the screw 17, while of course a release of the screw 17 will release the rod 7 for any subsequent adjustment. With this construction the front upper corner portions of the ends 2 of the showcase are held and secured against any tendency to warp or spring outward or otherwise separate from the end edges of the upper or top glass plate 3.

In Figs. 7 and 8 the invention is applied to a different form of showcase, in which there are three sections, 3a, 3b and 3c disposed, as shown in Fig. 7, at angles to each other. One of the end sections, for example 3c, will carry the rod 7 at its outer vertical end, while the other end section, 3a, at its vertical outer end will carry the anchoring block 11. The connecting metal ribbon in three sections, 9a, 9b and 9c, corresponding to the three sections of the showcase, have the adjacent ends of said ribbon sections spot-welded to angle blocks 18 which are located at the front upper corners where the sections 3a, 3b and 3c come together. In this manner the ribbon sections 9a, 9b and 9c are made in effect integral but with a change in direction to correspond with the change in direction in the fronts of the sections of the case. The connection of one end of the member 9a to the anchor block 11 and of the member 9c to the rod 7 is the same as before, the rotation and tightening by rotating the rod 7 is the same and the holding of the rod 7 in any position to which rotatively adjusted is accomplished in the same way.

The construction described, while of a relatively simple character, is very practical, useful and effective for the purposes for which it has been produced.

The invention is defined in the appended claims and is to be considered comprehensive of all forms of structure coming within their scope.

40 I claim:

1. In a structure of the class described, an enclosure having a bottom, vertical ends, front and top, tie means anchored at one end thereof on one of said vertical ends at its upper portion and 45 extending underneath said top across to the other vertical end, and rotatable means to which the other end of said tie means is connected extending substantially perpendicular to said tie means for tensioning the same to thereby hold said ends 50 from outward warping or spreading at their upper portions.

2. A showcase structure comprising, a bottom, vertical ends, a glass front and a glass top, a horizontal bar connecting the rear upper corners 55 of said ends, a strip of metal anchored at one end to the upper edge portion and adjacent the front edge of one of said vertical ends of the showcase, and extending horizontally underneath said top to the upper front corner of the opposite vertical end of the showcase, and a 60 rotatable member extending substantially perpendicular to said strip to which the other end of the metal strip is secured, combined with means for mounting said rotatable member on said other vertical end of the showcase whereby it may be turned to impart tension of said metal strip.

3. A construction containing the elements in combination defined in claim 2, said vertical ends 70 at their upper edges and lengthwise thereof each having an upwardly extending rib located against the adjacent end edge of said top, said ribs being drawn against the end edges of said top upon tensioning said metallic strip.

76 4. A showcase comprising, a bottom, vertical

ends, a glass top, and a glass front, a horizontal bar extending between and connecting the rear upper corner portions of said ends of the showcase, an elongated thin strip of metal anchored at one end to the front upper corner portion of one of the vertical ends of the showcase and extending horizontally underneath said top to the front upper corner of the opposite vertical end of the showcase, a rod located lengthwise of and at the upper edge portion of said last mentioned vertical end of the showcase, the other end of said metallic strip being connected thereto whereby rotating the rod about its axis in one direction will tend to shorten said strip, said rod at its rear end being accessible at its back of the showcase and having means at its rear end for application of a tool thereto to rotate said rod.

5. A construction containing the elements in combination defined in claim 4, combined with a pressure block mounted adjacent and adapted to bear at one end against a side of the rotatable rod, and means for releasably forcing said pressure block against the rod to frictionally engage and hold it from rotation.

6. A construction containing the elements in combination defined in claim 4, combined with a block at the rear upper portion of the showcase through which the rear end of said rod passes, said block having a recess at its inner side through which the rod passes, the end of said recess farthest away from the rod being inclined to the plane of said block, and a member located in said recess shaped to bear at one end against a rounded surface of the rod and at the other end inclined to correspond with the inclined end of said recess, and means operable from the rear side of the block for moving said member inward into said recess and thereby imparting a longitudinal movement thereto to press it against said rod, as specified.

7. A showcase comprising, a bottom, vertical ends, a glass top and a glass front, means connecting the rear portions of said vertical ends to hold them against outward warping or spreading, and an elongated thin metal strip located underneath the front portion of the top and extending between the upper corner portions of said vertical ends and connected at one end to one corner portion, combined with manually operable rotatable means connected with the other end of said metallic strip and extending substantially perpendicular thereto for adjusting its effective length and providing tension between the front upper corners of said vertical ends of the showcase to hold them against outward warping and spreading.

8. In a structure of the class described, an enclosure having a bottom, vertical ends, front and top, tie means anchored at one end thereof on one of said vertical ends at its upper portion and extending underneath said top across to the other vertical end, means to which the other end of said tie means is connected extending substantially perpendicular to said tie means for tensioning the same to thereby hold said ends from outward warping or spreading at their upper portions, and means including a block movable toward and away from said tensioning means for releasably holding same in any position to which it is adjusted.

9. A showcase having a bottom, vertical ends, a glass front and a glass top, said ends at their upper edges having upwardly extending longitudinal ribs at their outer sides within which

the end edges of said top are received, tie means extending between the upper front corner portions of said vertical ends and located underneath the top, said means being connected at 5 one end to one vertical end of the showcase, and rotatable means connected to the other end of

said tie means, extending from the front to the rear of the case to adjust the tension of said tie means whereby said ribs may be held against the adjacent end edges of the top.

ANTHONY VANDERVELD.
